DESIGN FOR A FRAME FOR EYEGLASSES

Morris Schwartz, Sunnyside, N. Y.

Application May 3, 1946, Serial No. 129,258

Term of patent 14 years

(Cl. D57—1)

To all whom it may concern:

Be it known that I, Morris Schwartz, a citizen of the United States, residing at Sunnyside, county of Queens, and State of New York, have invented a new, original, and ornamental Design for Frame for Eyeglasses, of which the following is a specification, reference being had to the accompanying drawing, forming part thereof.

Fig. 1 is a front elevational view of a frame for eyeglasses, showing my new design.

Fig. 2 is a side elevation.

I claim:

The ornamental design for a frame for eyeglasses, as shown.

MORRIS SCHWARTZ.
